Carman E. Campbell

UNITED STATES PATENT OFFICE

EDWARD J. NOBLE, OF NEW LONDON, CONNECTICUT, ASSIGNOR TO GILLETTE-VIBBER COMPANY, INCORPORATED, OF NEW LONDON, CONNECTICUT, A CORPORATION OF CONNECTICUT

RIGID CONDUIT GROUND CONNECTER

Application filed March 9, 1929. Serial No. 345,665.

My invention relates to the improvement in a rigid conduit ground connecter and the novelty consists in the adaptation and arrangement of parts as will be more fully hereinafter pointed out.

Although flexible conduits are now extensively used in many electrical wire installations, there are still many types of construction in which the rigid pipe conduit is still used for carrying electrical wiring because of appearance or special requirements which specify this type of conduit.

The ground connecters now in general use in connection with rigid pipe conduits require soldering or some complicated method of securing the ground connecter to the conduit.

My device has overcome the necessity of such prolonged hand labor, furnishing a unit which is adapted to be threaded on to the standard conduit pipe which is threaded at its terminal to receive the same, whereby the expense of installation is substantially cut down and a more perfect connection is made which can be readily disconnected at any time, although the connection is secure and permanent against accidental breaking of the connection.

Referring to the drawings, Figure 1 is a top plan view of my device connected to a rigid conduit and ground pipe, both of which are broken away for convenience in illustration.

Figure 2 is a vertical section on the line 2—2 of Figure 1.

Figure 3 is a side elevation of Figure 1.

In the drawings 4 is a rigid conduit having a threaded portion 5 at its terminal end and in which is mounted a wire 6 having the usual insulation 7. My ground connecter has a rigid coupling portion 8 which is internally threaded at 9 and a rigid extension portion 10 to which is secured by means of rivets 11 a flexible clamping member 12 which has a large wire pocket 13 tapering into a smaller wire pocket 14 and having an opening or outlet 15 and a series of holes 16 adapted to be engaged by the usual bolts 17 and nuts 18 whereby the flexible clamping member 12 may be clamped around on ground pipe 19 in the usual well known manner, the particu-

lar holes 16 being used which will accomplish this on the particular size ground pipe 19 which may be used.

In mounting my device, the terminal end of the rigid conduit 4 will be threaded at 5 in the usual well known manner and the internally threaded rigid coupling portion 8 will thread on to said threading 5 thereby securing my ground connecter rigidly on the rigid conduit 4. The wire 6, carrying insulation 7 will be brought down through the rigid conduit 4 in the usual well known manner and because of the large wire pocket 13 can be brought through my ground connecter readily, and the insulation 7 can then be removed from the end of the wire 6 whereupon the stripped wire can be placed in the smaller pocket 14 and brought through the outlet 15 and as the bolts 17 and nuts 18 are placed in the particular openings 16 to tighten down the flexible clamping member 12 to the desired position on the ground pipe 19 whereby the wire 6 will be clamped in a rigid position in contact against the ground pipe 19 with the end portion projecting out through the outlet 15.

It is thus seen that my device effects a rigid connection with the rigid conduit pipe and establishes a positive ground by the wire of the conduit circuit directly on the ground pipe through a flexible clamping member adapted to fit any conduit ground pipe which it may be necessary to use, whereby a perfect grounding of the electrical circuit carried in the rigid conduit is effected through a connector which entirely encases the grounding portion of the circuit thereby protecting it completely against dirt and moisture or breakage, whereby a perfect grounding of an electrical circuit carried in a rigid conduit is readily established and positively maintained under any and all conditions.

It will be apparent that many variations may be made in my particular structure without departing from the spirit and intent of the invention.

I claim:

1. A ground connecter comprising the combination of a rigid threaded coupling having an extension member, a ground pipe

flexible clamp rigidly secured to said extension member and consisting of a portion having a large wire pocket tapering into a smaller pocket and a further extended end portion, bent back and covering the large pocket portion, and fastening means for securing the end in position.

5 2. A ground connector comprising the combination of a rigid coupling means for a rigid conduit, a means fixedly secured thereto at one end and having a large ground wire pocket tapering into a groove pocket and outlet and the opposite end of said flexible clamp turned back and covering the large pocket portion, and means for detachably securing said opposite end in position.

10 3. A ground connector comprising the combination of a rigid coupling means for a rigid conduit, a flexible ground pipe clamping means rigidly secured thereto at one end and having a large ground wire pocket tapering into a groove pocket having an outlet and adapted to be folded back and detachably secured at its outer end to cover said large pocket whereby a ground wire carried therein is entirely encased between said rigid conduit and around said ground.

15 4. A ground connector comprising the combination of an internally threaded rigid conduit connector having an extension member, a flexible ground pipe clamp rigidly secured to said extension and having a large ground wire pocket tapering into a smaller pocket and an outlet, said clamp bent back and covering said large pocket, and separable fastening means for securing the end in position whereby said ground wire is maintained entirely encased from said rigid conduit to and around said ground.

20 40 5. A ground connector comprising the combination of a rigid internally threaded coupling having an extension semi-cylindrical lip member, a flexible ground pipe clamp rigidly secured at one end to said lip member, a large semi-cylindrical wire pocket similar to and running from said extension lip into a small wire pocket terminating in a wire outlet, said clamp running around said ground and being turned back over said large pocket to entirely encase a ground wire and means for detachably securing the other end of said clamp to said lip.

In testimony whereof I affix my signature.

EDWARD J. NOBLE.
